OVEREDGE SEWING MACHINE

Ned L. Wallenberg, Chicago, and George Sauer, Berwyn, Ill., assignors to Union Special Machine Company, Chicago, Ill., a corporation of Illinois

Application December 7, 1948, Serial No. 63,924

5 Claims. (Cl. 112—256)

1

This invention relates to sewing machines and more particularly to machines adapted to produce overedge stitching, of either the two-thread or three-thread type. It relates especially to the lubrication of the various operating parts of such machines.

In accordance with modern practice, machines of the character indicated, used for overedging underwear and the like, are operated at high speeds which exceed those of most, if not all, other types of sewing machines. Speeds of over 5000 stitches per minute are common and efforts are constantly being made to increase the speed of overedgers to 6000 stitches per minute. Operation of the driven parts at such high speeds greatly increases the problem of effecting adequate and proper lubrication, without undue deterioration of the lubricant and without discharging lubricant onto portions of the work or the threads or onto surfaces engaged by these or by the operator.

A primary object of the invention has been to provide effective and efficient lubrication for all of the relatively moving parts of an overedge sewing machine, operated at high speed, without spattering or otherwise depositing lubricant on the work, or the stitching threads or the operator.

Another important object has been to provide such lubrication with a minimum of agitation and working of the lubricant so that rapid deterioration of the lubricant is avoided.

As an incident to the foregoing, it has been a further object to reduce to a minimum the amount of effort or power expended in bringing about the required distribution of the lubricant. This is of particular importance in the starting of a seaming operation. Means heretofore employed for distributing lubricant, in machines of the type to which the invention is directed, have interfered with the rapid acceleration of the machines from an idle to a full speed operating condition. This has resulted in uneven stitch formation since the character of the stitch is influenced to a considerable extent by the speed at which the machine is driven. Machines designed to produce a particular character of stitch at a predetermined speed will not produce the desired result at the slower speeds involved during the periods of acceleration. By the present invention the machine is permitted to come up to full speed rapidly so that a relatively small portion of each seam is formed under conditions other than those intended. The importance of this will be appreciated when it is considered that

2

seams are frequently quite short so that a machine is started and stopped at very frequent intervals in the course of its continuous use.

Another object of the invention has been to render readily accessible certain operating parts requiring frequent access for adjustment and the like, while at the same time providing adequate lubrication therefor. Certain parts of the work feeding mechanism are in this category.

10 A special feature of the invention is the provision for grease lubrication of certain bearings which extend through the walls of an enclosed housing while the mechanism within the housing is lubricated by a fine spray or mist of a liquid lubricant. The heavy grease thus serves the double function of lubricating certain important bearings and providing a seal around shafts which extend through the wall of the housing. Incidental to the foregoing is the provision of needle bearings for the main rotary shaft and certain rock shafts of the machine.

Another special feature is the construction of the housing in two main separable parts with a removable cover for the upper part and a removable base for the lower part to facilitate access to the interior. The arrangement is such that several rock shafts, identified with the needle carrying member and a reciprocating trimmer, are carried by the upper part of the housing while the main driving shaft is in the lower part. Removal of the cover permits easy access to the driving connections for their disconnection whenever it is desired to separate the upper and lower parts of the housing. By virtue of this construction, it has been possible to locate the axis of the rock shaft on which a curved needle carrier is mounted, and by which it is operated, very close to the plane of the work supporting surface. As a result, needle cutting of the work is substantially eliminated, since the needle enters the work substantially normal thereto.

45 A further feature of the invention is the formation of the removable top with a slope and a curvature adapted to insure proper distribution of the lubricant which is thrown against it by the dispersing or mist producing means. Ribs or pointed projections extending downwardly from the sloping top also assist in delivering the lubricant to the desired points.

50 Special means are also provided for delivering lubricant, in just the required amounts, to various operating parts, outside of the main housing, which cannot be lubricated directly by the mist.

Other objects, features, and advantages of the

invention will appear from the detailed description of an illustrative form of the same which will now be given in conjunction with the accompanying drawings, in which:

Fig. 1 is an end elevational view of the machine, as seen from the operator's left;

Fig. 2 is a front elevational view of the machine, with a portion of a cover element broken away to show the parts behind it;

Fig. 3 is a longitudinal vertical section through the machine;

Fig. 4 is a detail view, in end elevation, of an integral rock shaft and arm provided in the machine;

Fig. 5 is a longitudinal section through the element of Fig. 4;

Fig. 6 is a transverse sectional view, taken substantially along the line 6—6 of Fig. 7;

Fig. 7 is a horizontal sectional view through the machine, taken substantially along the line 7—7 of Fig. 6;

Fig. 8 is a transverse, vertical section, taken substantially along the line 8—8 of Fig. 3;

Fig. 9 is a detail view, in end elevation, of a rock shaft and its connected arm forming an element of the machine;

Fig. 10 is a longitudinal sectional view along the line 10—10 of Fig. 9;

Fig. 11 is a detail view in horizontal section through a portion of the frame of the machine taken substantially along the line 11—11 of Fig. 3;

Fig. 12 is a detail view, in vertical section along the line 12—12 of Fig. 7;

Fig. 13 is a detail view, in vertical section along the line 13—13 of Fig. 7;

Fig. 14 is a detail view, in vertical section along the line 14—14 of Fig. 11;

Fig. 15 is a front elevational view of a modified form of the left hand portion of the frame structure shown in Fig. 2;

Fig. 16 is a detail view, partly in elevation and partly in vertical section, showing the needle carrier and movable trimmer arm and associated parts; and

Fig. 17 is a detail view showing in plan the movable trimmer arm and associated parts.

Referring now to the drawings, and particularly Fig. 3, the frame of the machine comprises a base plate 10 on which is mounted a housing that is divided horizontally into two sections, the lower section 11 being secured to the base by screws or the like. A gasket 10a is provided between section 11 and the base plate. The upper section 12 of the frame may be separated from the lower section 11 along the line 13 (Figs. 3 and 6) and is secured to the lower section by a series of screws 14 (Figs. 6 and 7). The major portion of the top of the enclosed chamber is enclosed by a removable cover 15, a gasket 16 being provided between the edges of the cover and the edges of the top section 12. Screws (not shown) which are preferably countersunk in recesses 18 in the cover (Fig. 2) serve to retain the cover on the upper section of the frame. The four members, 10, 11, 12, and 15, serve to form an enclosed chamber for housing the major portion of the operating mechanism of the machine, this chamber being substantially oil-tight and adapted to retain lubricant to the level indicated at 19 in Figs. 3 and 6.

An extension 20 at the left end of the lower section 11 of the frame (Fig. 3) serves to provide the lower portion of a substantially enclosed auxiliary chamber 21. Extension 20 cooperates

with the gasket 10a between the section 11 and base plate 10. A lateral extension 22 of the portion 20 of the frame (Figs. 1 and 2) carries a pedestal 23 which, as best shown in Fig. 2, may be suitably formed to provide a horn 24 which projects toward the left (Fig. 2) from the line of seam formation. This horn, it will be understood, may be used to facilitate the overedge stitching of tubular work. When the horn is used, a work support 25 is swung outwardly into inactive position. This work support, as shown in Figs. 1 and 8, is adapted to pivot about a pin 26 mounted in a boss 27 projecting from the rear side of the frame portion 20. A collar 28, secured to the work support 25, is adapted to swivel with the latter about the axis of the pin 26. If desired, the horn 24 may be eliminated and the modified form of pedestal 23a, shown in Fig. 15, may be used. In this modified construction the work support 25a may be fixed, if desired, and the bracket 31 may be omitted.

The section 20 of the frame is recessed, as indicated at 29 in Fig. 1, to provide a space for thread tensioning means 30 and other thread control elements in a readily accessible position. A bracket 31 (Fig. 3) having an inner wall 32 is mounted in the recess in the member 20 to provide the exposed space 29 and, at the same time, partially enclose the auxiliary chamber 21. An upwardly extending portion 33 of the frame section 12 has a contour merging with that of the cover 15 and is provided with an outwardly extending hollow boss 34 adapted to receive and retain thread tensioning and guiding means 35 for the needle thread.

A horizontally swingable cloth plate 36, providing an extension of the work support 25, is adapted to be swivelled about a pin 37 retained by a lug 38 projecting from the forward wall of the frame section 11 (Figs. 1, 6 and 7). A collar 39, secured to the cloth plate, serves to retain the latter in its desired horizontal position, while at the same time permitting it to swivel about the axis of the pin 37.

Integral with the part 33 of the upper section of the frame is an outwardly extending head 40 (Figs. 1 and 2) adapted to retain a vertically slideable presser bar 41. The latter is normally urged downwardly by a spring 42 whose tension may be varied by turning a thumb screw 43. A lateral projection 44 of the presser bar extends over the end of a lever 45 secured to one end of a shaft 46 which passes through the frame from the front to the back thereof. A spring 47 normally urges the lever 45 in a counterclockwise direction (Fig. 2) to a position in which a slight clearance is provided between the end of the lever and the projection 44. Lifting of the presser bar against the action of spring 42 may be brought about by rocking the shaft 46 in a clockwise direction. For this purpose, as best shown in Figs. 1 and 6, the end of the shaft 46 which projects from the rear of the frame has secured thereto an arm 48 which is clamped to the shaft by means of a screw 49. The arm 48 is L-shaped and it will be understood that it has a portion extending horizontally in a direction perpendicular to the shaft 46 and another portion 48 parallel with the shaft 46. The outer end of this parallel portion is provided with an eyelet 50 adapted to receive a rod or chain to connect it with a foot treadle, or knee control, or the like. A presser foot 41a (Figs. 1, 2 and 6) of any suitable construction, preferably pivoted to the lower end of the bar 41, serves to urge

the work against the throat plate portion of the cloth plate.

Referring particularly to Fig. 3, a main driving shaft 51 passes through the enclosed chamber and extends beyond the end walls thereof. Adjacent its left end the shaft 51 is supported by a plain bearing 52, preferably formed in two parts which are held together by a ring 53. The latter fits snugly in an opening in a wall 54 forming part of the lower section 11 of the frame. Construction of the bearing in the manner explained permits introduction of the main shaft, with its various cranks to be hereinafter described, into the frame from the left end of Fig. 3. Enlarged disc-like portions 55 and 56 at the opposite ends of the journaled portion of the shaft serve to minimize the escape of lubricant from the enclosed chamber. Adjacent its right end, the shaft 51 is preferably supported by a pair of needle bearing units 57 and 58 mounted in a sleeve 59 carried by the end wall of the lower section 11 of the frame. Sleeve 59 has a radially extending flange 60 which is secured by screws 61 to the end wall of the frame. Discs or washers 62 and 63, at the opposite ends of the sleeve 59, serve to retain the needle bearing units within the sleeve and to form a closed, grease-tight chamber for the housing of these units. The outer free end of the shaft 51 carries a combined handwheel and pulley 64 which is secured to the shaft by a set screw 65. Provision is made for lubricating the needle bearings 57 and 58, preferably by means of heavy grease forced under pressure into the chamber formed within the sleeve 59. For this purpose a pressure gun fitting 66, which may suitably be of the "Zerk" type, is mounted in a cup 67 which, in turn, fits in a recess in the hand wheel 64. Cup 67 has a screw threaded shank 68 cooperating with internal screw threads in the end of the shaft 51. It will be understood that an axial passage is provided from the fitting 66 through the shank 68 to a bore in the end of the shaft 51. This bore, in turn, communicates through radial passages with the outer surface of the shaft. Fitting 66 is provided with a ball valve or the like.

The stitch forming devices of the machine include a curved needle 69 suitably clamped in an arm 70 secured to, or formed integral with, a rock shaft 71. This rock shaft is supported by a pair of needle bearing units 72 and 73 carried by an inwardly and outwardly extending boss formed on the member 33 of the frame. Washers 74 and 75, at the opposite ends of the bearing assembly, assist in retaining the parts in proper position and serve to form an enclosed chamber. Provision is preferably made for forcing a heavy grease type of lubricant under pressure through a "Zerk" type fitting 76, or the like, into an axial bore and out through radial passages in the shaft 71. The inner end of shaft 71 carries an arm which is preferably provided with a split hub 77 by which it may be clamped to the shaft. A pitman 78 is pivotally connected with the outer end of the arm and carries at its opposite end a strap 79 cooperating with a crank portion of the shaft 51. Through these connections the needle will be reciprocated through a curved path upon each revolution of the shaft 51. It will be noted, in this connection, that the axis of the shaft 71 is substantially in the plane of the work supporting surface 25. By virtue of this, the pointed end of the needle 69 enters the work in a direction substantially perpendicular to the

work support. In this way the danger of needle cutting of the work is reduced to a minimum.

Cooperating with the needle, as it passes through the work to a point below the work support, is a looper 80 (Figs. 1 and 2). This is fastened by screws 81 to an arm 82 (Fig. 11) secured to or formed integral with a rock shaft 83. The latter is journaled in suitable bearings 84, 85 and 86, carried by outwardly extending projections of the wall 54. Within a recessed portion 87 of this wall, there is secured, by means of screws or the like, the hub 88 of an arm 89 having an L-shape, as shown in Fig. 11. From the outer end of arm 89 a ball stud 90 projects, this ball stud being received by a strap 91 at the lower end of a pitman 92 which has at its opposite end a strap 93 cooperating with a spherical crank portion 94 of the shaft 51. Through the connections described the overedge looper element 80 will be oscillated upon each revolution of the shaft 51.

An overedge looper 95 of the elbow form is pivotally secured by means of a screw-stud 96 to the outer end of an arm 97, preferably formed integral with a rock shaft 98 (Figs. 4 and 5). The arm has a threaded opening 98a to receive the stud. Shaft 98 is suitably journaled in a bearing sleeve 99 (Fig. 8) carried by an upwardly extending wall or partition 100 within the auxiliary chamber 21. At its lower end the overedge looper is pivotally secured, by means of a screw-stud 101, to the outer end of an arm 102 preferably formed integral with a rock shaft 103 (Figs. 9, 10, and 11). Arm 102 has a threaded opening 101a to receive the end of the screw-stud. Rock shaft 103 is journaled in a bearing sleeve 104 carried by the wall 100. At its inner end, within the auxiliary chamber, a cap-like sleeve 105 is secured to the shaft, this sleeve having a radially extending ball stud 106. The latter cooperates with a strap 107 at the lower end of a pitman 108 (Fig. 3) having a strap 108 at its upper end surrounding a spherical crank portion of the shaft 51. Through the connections described the overedge looper will be given a combined bodily and pivotal movement which serves to carry its thread retaining end from a point below the work, upwardly and over the edge of the work to a point in the path of the needle for the formation of a three-thread, overedge stitch. If desired, the overedge looper may be replaced by a spreader having simply a notched end which will serve to receive the looper-thread from the under looper and carry this around and over the edge of the work into the path of the needle. It will be understood that the relative timing of the needle and the two loopers is such as to provide the desired stitch.

The work feeding mechanism of the illustrative machine is of the differential feed dog type, the general mode of operation of which is similar to that of the mechanisms disclosed in the patents to Zeier, et al. No. 1,884,489, granted October 25, 1932, and Sauer No. 2,009,747, granted July 30, 1934. It comprises a main feed dog 110 (Fig. 7) and an auxiliary feed dog 111 adapted to receive a differential movement in relation to the main feed dog. These feed dogs are given four motion movements by the mechanism to be presently explained.

The main feed dog is carried by the outer end of a feed bar 112 (Figs. 3, 7 and 8) having an elongated guide slot therein, the top and bottom surfaces of which are adapted for sliding movement in relation to a pair of blocks 113 carried by a

crank portion of the main shaft 51, between radial flanges 114 and 115 (Fig. 3). Rotation of the shaft 51 serves to impart lifting and lowering movements to the feed dogs through the up and down movement of the blocks 113. The feed bar has a rearward extension 116 pivotally connected by a pin 117 with a rocker 118 secured to a rock shaft 119 (Fig. 8). The auxiliary feed dog 111 has a downward extension secured by a screw 120 to a block carried by a rod 121 slidably mounted in bearings provided in lateral extensions 122 and 123 of the feed bar 112. Intermediate the bearings, the rod carries a block 124 adapted to be adjustably secured to the rod by means of screws 125. A stud 126, extending laterally from the block 124, provides for the pivotal attachment thereto of one end of a link 127, the opposite end of which is swivelly mounted upon a bolt 128 adapted to be secured in any desired position along an arcuate slot 129 provided in an extension 130 of the feed rocker. By suitable selection of the position of the bolt 128, the auxiliary feed dog may be given either greater or smaller movements than the main feed dog, depending upon the character of the work being overedged.

Turning now to Fig. 12, the shaft 119, to which the feed rocker 118 is secured, is journalled at one end in a bearing sleeve 131 carried by the frame section 11 and it is journalled at an intermediate point in a bearing sleeve 132, also carried by the frame. A collar 133 secured to the shaft serves to retain it against endwise movement toward the left. At the opposite side of the bearing sleeve 132 the shaft carries a hub or sleeve 134, secured by screws 135 to the shaft. This sleeve has an upwardly extending, integrally connected arm 136 which passes through an aperture provided in a raised portion 137 of the base of the main enclosed chamber. Arm 136 has an elongated, arcuate slot 138 (Fig. 6) adjacent its upper end adapted to receive a bolt 139. The latter may be adjusted to any desired position along the slot 138 to vary simultaneously the feed stroke imparted to the two feed dogs. Bolt 139 has a spherical portion adapted to receive a strap 140 at one end of a pitman 141, the opposite end of which has a strap 142 surrounding a crank portion of the main shaft 51. Through the connections described, the feed bar 112 will be given the feed stroke and return movements desired.

To prevent the escape of lubricant from the main chamber around the arm 136 a washer-like element 143 is provided around the arm, this element having an opening arranged to snugly receive the arm and yet permit relative sliding movement between the two. It is held against the top surface of a shelf-like portion 144 of the raised part of the base of the chamber by means of a spring 145 secured by a screw 146 to the shelf. To keep to a minimum the lubricant which tends to accumulate on the raised portion of the base, the latter, for the most part, merges along a curved wall 147 with a vertical wall 148. Thus any lubricant which may be deposited on the elevated portion of the base tends to drain back to the lower sump.

Means are also provided for trimming the edge of the work in advance of the formation of the overedge stitching at said edge. This means comprises a stationary trimmer blade 149 (Figs. 1 and 8) mounted in a slide block 150 adjustably carried by the pedestal 23. A screw 151 is provided for adjustment of the block 150 in the pedestal and a screw 152 serves to clamp the block in adjusted position. Cooperating with the sta-

tionary trimmer blade is a movable blade 153 (Fig. 2) which is of inverted L-shape in cross-section. This blade is carried by a head 154 to which it is secured by a screw 155 which permits adjustment of the movable blade to conform with the adjustment of the stationary blade. Head 154 is formed integrally with an arm 156 (Figs. 3, 7, 16 and 17). The opposite end of the arm 156 has a hub 157 integral therewith, which is integrally or otherwise connected with a rock shaft 158 journalled in needle bearings 159 and 160 carried by the same boss on the wall 33 of the housing which carries the needle rock shaft 71. Washers or sealing discs 161 and 162 are provided on shaft 158 at the opposite ends of the boss to form an enclosed chamber for the needle bearings. On the inner end of the shaft 158, which extends into the enclosed chamber of the housing, there is clamped a sleeve 163 (Figs. 6, 7 and 13) having integral therewith an arm 164 carrying a ball pin 165. The latter is received within a strap 166 at the upper end of a pitman 167, the lower end of which is provided with a strap 168 cooperating with a crank portion of the shaft 51. Through the connections described the shaft 158 is rocked upon each rotation of the main shaft to carry the movable blade 153 downwardly through the work adjacent its edge to shear the edge to a desired line in cooperation with the stationary blade 149. To guide the arm 156 in its rocking movements and prevent its deflection as it shears the edge of the work a block 169 is secured, by screws or the like, to the inner side of the arm and this block is arranged to cooperate with a guide block 170 secured by screws to an adjacent portion of the frame. (See Figs. 16 and 17.) Shaft 158 is preferably provided with an axial bore and radial openings for the delivery of heavy grease under pressure to the needle bearings. A suitable fitting 171, of the "Zerk" type or the like, is provided at the outer end of the shaft to permit the introduction of the grease.

Adjacent the center of the enclosed chamber of the housing, a disc 172 is secured to the shaft 51 for rotation therewith. The disc is preferably slightly cupped or saucer-shaped and has a hub 173 secured to the shaft by screws 174. The arrangement is such that a small portion of the edge of the disc is always immersed in the lubricant in the base of the chamber. As the disc is rotated, it picks up small quantities of the lubricant and this is thrown by centrifugal force against the sides and top of the housing in the form of fine droplets. The arrangement is such that the entire interior of the housing becomes filled with a fine lubricant mist. None of the other driven parts are brought into contact with the lubricant so that there is no excessive churning of the oil and little resistance is offered by the lubricant to the turning of the main shaft. Acceleration of the machine, on starting up, is therefore not retarded by the lubricant.

A portion of the mist within the housing will deposit its lubricant directly upon surfaces requiring lubrication. Other portions will find their way indirectly to surfaces to be lubricated. For example, some will collect on the under surface of the top 15 and gradually flow down the slope of the latter; some of this will, in turn, flow downwardly along conical projections 175 and 176 from the points of which drops of lubricant will be deposited on various parts of the mechanism, as best illustrated in Figs. 3 and 6. Some of the lubricant will be picked up by the wicks, best shown in Figs. 6 and 7, and delivered thereby to

points outside of the enclosed housing. Thus, a wick filled tube 177 has its wick extending into the housing where it serves to pick up a small amount of lubricant and deliver it to the feed rocker. A wick filled tube 178 similarly serves to pick up and deliver lubricant to the pivotal connection of link 127 with the feed rocker. Another wick filled tube 179 serves to pick up and deliver lubricant to the bearing 123 for the slide rod 121. A further wick filled tube 180 serves to deliver some of the lubricant to the strap 169, while another wick filled tube 181 serves to deliver lubricant to the bearing between link 127 and pin 126. Other wick filled tubes may, if desired, be employed to deliver lubricant to various other points outside of the main housing.

Some of the lubricant, so delivered outside of the housing, will accumulate in the sump 21 (Fig. 8) and may be delivered by other wicking from this point to various surfaces to be lubricated. For example, wicking 182 may extend downwardly from the shaft 103 to pick up some of this excess lubricant. This wicking extends through the length of the shaft 103 and upon oscillation of the latter serves to deliver the lubricant, by centrifugal force, through a radial passage 183 (Figs. 9 and 10) in the arm 102 and outwardly through a passage 184 to lubricate the connection between arm 102 and the overedge looper 95. A similar arrangement may be provided for lubricating the pivotal connection between this looper and the arm 97. For this purpose, wicking 185 (Fig. 3) extending from the bore of the shaft 98 may pass to a suitable point within the auxiliary chamber 21. This wicking may pass through an aperture in the bracket 32, for this purpose. Lubricant so delivered to the bore of the shaft 98 may be thrown, by centrifugal force, through a radial passage 186 (Figs. 4 and 5) in the arm 97 and discharged through an aperture 187.

At the front of the machine (Fig. 2) a pivoted cover plate 188 is provided to normally conceal and enclose the loopers and certain of the thread handling means. This cover is hingedly carried by a pin 189 supported by hinge members 190 formed on a plate 191 secured by screws 192 to the base of the machine. A spring 193 serves to hold the cover normally against the frame of the machine but when access to the thread handling devices is desired the cover may be drawn outwardly by a handle 194.

It will be understood that various accessory devices will be provided. These include appropriate thread handling means, some of which are illustrated but need not be described since they form no part of the invention to be claimed herein. Other accessory devices include a lubricant gage 195, formed of Lucite or the like, adapted to indicate at the top of the housing the level of the lubricant within the housing.

While an illustrative form of the invention has been disclosed in considerable detail, it will be understood that various changes may be made in the construction, arrangement, and operation of the various parts without departing from the general principles and scope of the invention. Thus, while heavy grease lubrication has been disclosed with respect to certain bearings ordinary oil lubrication may be provided instead. For this purpose, means may be employed for directing some of the lubricant collected from the mist in the main housing to the small chambers enclosing the needle bearings.

What we claim is:

1. An overedge sewing machine adapted for

high speed operation having a frame providing a relatively low enclosed lubricant retaining housing forming the major portion thereof, an extension at one side of the lower portion of said housing providing a work supporting surface, a main driving shaft extending through said housing and into said extension, a needle carrying member driven by said shaft from within said housing and arranged to reciprocate a needle from a point above said work supporting surface to and through the same, complementary stitch forming devices within said extension cooperating with said needle both below and above said work supporting surface, work feeding means in said extension, operating connections to said needle carrying member, said complementary stitch forming devices and said work feeding means driven by said main shaft within said housing, substantially all of said operating connections being below the work supporting surface, the portion of said connections within the housing being at all times entirely above the lubricant level therein, a member carried by said main shaft arranged to rotate therewith and extending continuously into the lubricant in said housing for dispersing the same as a mist throughout the interior of the housing, and wicking exposed to said mist within the housing and extending through a wall of said housing for delivering lubricant derived from said mist to relatively moving surfaces of said stitch forming devices and work feeding means exterior of said housing.

2. An overedge sewing machine having a frame providing a relatively low enclosed lubricant retaining housing forming the major portion thereof, an extension at one side of the lower portion of said housing providing a work supporting surface, a main driving shaft extending through said housing and into said extension, a needle carrying member driven by said shaft from within said housing and arranged to reciprocate a needle from a point above said work supporting surface to and through the same, complementary stitch forming devices within said extension cooperating with said needle both below and above said work supporting surface, work feeding means in said extension, operating connections to said needle carrying member, said complementary stitch forming devices and said work feeding means driven by said main shaft within said housing, substantially all of said operating connections being below the work supporting surface, the portion of said connections within the housing being substantially entirely above the lubricant level therein, a member carried by said main shaft and extending into the lubricant in said housing for dispersing the same as a mist throughout the interior of the housing, wicking exposed to said mist within the housing and extending through a wall of said housing for delivering lubricant derived from said mist to relatively moving surfaces of said stitch forming devices and work feeding means exterior of said housing.

3. An overedge sewing machine having a frame providing an enclosed lubricant retaining housing forming the major portion thereof, an extension at one side of the lower portion of said housing providing a work support, a main driving shaft extending through said housing and

into said extension, a needle carrying member driven by said shaft from within said housing and arranged to reciprocate a needle from a point above said work support to and through the same, complementary stitch forming devices within said extension cooperating with said needle both below and above said work support, work feeding means in said extension, operating connections to said needle carrying member, said complementary stitch forming devices and said work feeding means driven by said main shaft within said housing, the portion of said connections within the housing being substantially entirely above the lubricant level therein, said connections including a rock shaft and an arm secured to said rock shaft, a member carried by said main shaft and extending into the lubricant in said housing for dispersing the same as a mist within the housing, wicking extending through a wall of said housing for delivering lubricant derived from said mist to relatively moving surfaces of said stitch forming devices and work feeding means exterior of said housing, a lubricant collecting sump arranged to collect excess lubricant delivered to said surfaces exterior of the housing, and means for delivering said excess lubricant to other surfaces exterior of the housing, said last recited means including wicking extending from said sump to and through said rock shaft, and said arm having a lubricant passage communicating with said wicking.

4. An overedge sewing machine having a frame providing an enclosed lubricant retaining housing forming the major portion thereof, an extension at one side of the lower portion of said housing providing a work support, a main driving shaft extending through said housing and into said extension, a needle carrying member driven by said shaft from within said housing and arranged to reciprocate a needle from a point above said work support to and through the same, complementary stitch forming devices within said extension cooperating with said needle both below and above said work support, work feeding means in said extension, operating connections to said needle carrying member, said complementary stitch forming devices and said work feeding means driven by said main shaft within said housing, the portion of said connections within the housing being substantially entirely above the lubricant level therein, said connections to said work feeding means including a vertically disposed arm extending through a slot provided in a horizontally extending wall of said housing to a point exterior thereof, sealing means car-

ried by said arm and cooperating with said slot to seal the same at all times, and a member carried by said main shaft and extending into the lubricant in said housing for dispersing the same as a mist within the housing.

5. An overedge sewing machine having a frame providing an enclosed lubricant retaining housing forming the major portion thereof, an extension at one side of the lower portion of said housing providing a work support, a main driving shaft extending through said housing and into said extension, a needle carrying member driven by said shaft from within said housing and arranged to reciprocate a needle from a point above said work support to and through the same, complementary stitch forming devices within said extension cooperating with said needle both below and above said work support, work feeding means in said extension, operating connections to said needle carrying member, said complementary stitch forming devices and said work feeding means driven by said main shaft within said housing, the portion of said connections within the housing being substantially entirely above the lubricant level therein, said connections to said work feeding means including an arm extending substantially vertically through a slot provided in an elevated portion of the bottom wall of said housing to a point exterior thereof, sealing means carried by said arm and cooperating with said slot to seal the same at all times, a rock shaft to which said arm is secured, said arm being adjustable angularly in relation to said rock shaft to vary the zone of operation of the work feeding means, said adjustment being effected exteriorly of the housing, and a member carried by said main shaft and extending into the lubricant in said housing for dispersing the same as a mist within the housing.
